UNITED STATES PATENT OFFICE.

DONALD E. WILLARD, OF DECATUR, ILLINOIS, ASSIGNOR TO ALLITH PROUTY COMPANY, OF DANVILLE, ILLINOIS, A CORPORATION OF ILLINOIS.

PINTLE-HINGE.

1,323,344.

Specification of Letters Patent.

Patented Dec. 2, 1919.

Application filed October 24, 1917. Serial No. 198,289.

To all whom it may concern:

Be it known that I, DONALD E. WILLARD, a citizen of the United States, residing at Decatur, in the county of Macon and State 5 of Illinois, have invented certain new and useful Improvements in Pintle-Hinges, of which the following is a specification.

My invention refers to hinges particularly to the type of hinge for use in swinging fire 10 doors and the like.

In installing swinging fire doors in masonry walls it has been customary to provide hinges extending beyond the face of the wall with which straps attached to the doors co- 15 operate, the wall member being generally provided with a pin and the strap member with an eye for fitting over said pin, the wall member being bolted in the wall. It will be understood that swinging fire doors for 20 the most part remain in open position that is, swung back against the wall leaving the passageway free and are closed only at night in some instances, or only when a fire occurs in the building which closing is brought 25 about usually by automatic means. When a door of the character described is allowed to remain in open position for some time, sagging occurs which sagging does no harm as long as the door is open but which pre- 30 vents proper closing of the door when moved into the door opening, thus defeating one of the purposes of such doors in not making a tight closure. Various means have been devised to overcome sagging but with- 35 out success.

The object of my invention is to provide a novel means for supporting a swinging fire door so that sagging is prevented.

A still further object is to provide a novel 40 pintle hinge for mounting swinging fire doors so that the line of thrust against one pintle will be counterbalanced by the line of thrust against the other and thus movement of the pintles prevented.

45 These and other objects will be apparent from the drawings, wherein—

Figure 1 represents an elevation of a swinging fire door mounted on a brick wall, the door being in closed position, the door- 50 way being indicated in dotted lines.

Fig. 2 is an enlarged view of the preferred embodiment of my invention.

Fig. 3 is a sectional view on line 3—3 of Fig. 2, and

Fig. 4 is a top plan view of the preferred 55 form of my invention.

5 represents the usual brick wall having therein the doorway 6 forming a passageway through the wall. For closing said doorway in case of fire, the fire door 7 is 60 provided this being of the usual well known construction made of metal adapted to prevent the passage of fire thereby. Firmly bolted to the door are upper and lower straps 8 and 9 forming portions of the 65 hinges and having at their outer ends eyes 10. The bracket or wall member which I prefer to employ comprises a wall flange or plate 11, a horizontally disposed body portion or arm 12 and an enlarged aperture 13 70 at the outer end of the body portion 12. Formed with the wall member 11 is a hood or box like portion 14 closed on the top and two sides and open at the bottom, the plate member 11 being provided with a slot 15 ex- 75 tending from the lower edge of the member 11 to a point slightly above the upper portion of the horizontal arm 12. Mounted within the aperture 13 at the outer end of member 12 is a pin 16 having a reduced portion 17 for entering said aperture 13, shoul- 80 der 18 being formed at the upper portion of the reduced part 17 forming a bearing against the upper surface of the member 12. It is with the pin 16 that the eyes 10 of the 85 straps 8 and 9 engage. For attaching the wall member to the wall, I prefer to employ a single bolt 19, over the head of which the slotted portion 15 of the bracket is slid with the hood embracing said head, the length of 90 the slot 15 being such as to position the wall flange 11 on the bolt so that the axis of the bolt is coincident with the point where the pin 16 delivers to the bracket a turning thrust caused by the straps 8 and 9 thus 95 bringing the turning thrust in actual alinement with this bolt, the result of which is that when such thrust is brought against the bracket no turning whatsoever will result as to the bolt is so positioned with respect to 100 the application of the turning thrust as to prevent any bodily displacement of the wall flange 11 through action on the pintle 16.

It will now be observed that the thrust to the left caused by the upper strap 8 and 105 the thrust to the right caused by the lower strap 9 will be directly in line with the centers of the bolts, hence, no turning of the

wall brackets will occur as the thrust is directly to the axes of the bolts. Swinging of the wall brackets about the bolts as centers is eliminated and consequently no sagging of the door occurs so that a perfect closing is made when the door is swung against the opening 6. If desired, two swinging doors may be mounted on each side of the wall 5 in which case the bolts 19 would be long enough to fasten the oppositely disposed brackets to the wall.

Such modifications as are permissible in a device of the class described I consider as coming within the scope of my invention.

15 I claim:

1. A hinge comprising in combination a wall member and a door member, the wall member having a plate of relatively substantial size, a projection therefrom adapted 20 to support the door member, a bolt extending through the plate at the center thereof, and arranged to lie in the line of thrust of the turning force applied to said door member whereby the turning of said plate is prevented.

2. In a hinge of the class described a door member and a wall member, the combination of a wall flange of relatively great area, a cover member integral with said 30 wall flange adapted to receive a bolt, said wall flange being provided with a slot extending from the lower edge thereof to substantially mid position of said cover, a horizontally extending member projecting 35 from said wall flange and provided at its outer end with a pin receiving aperture, the parts being arranged with the axis of the bolt in substantial alinement with the line of thrust imparted to said pin by said

door whereby said thrust is transmitted to 40 the said wall flange at the axial line of said bolt.

3. A hinge including in combination, a door member, and a wall member, the wall member having a vertically disposed wall plate with a slot extending from the lower edge upwardly, a hood overlying said slot, the parts being arranged to embrace the end of the bolt, an arm extending outwardly of said plate and hood with an enlarged end 50 portion, a pintle secured to said end portion for coöperating with the door portion, the whole being arranged so that the axis of the bolt includes the center of turning movement imparted to said wall member by the 55 door.

4. A hinge in combination with a door, of a headed bolt secured in the wall, the hinge having a wall member with a vertically disposed slotted wall plate for retention 60 by said bolt, the wall member also having a hood for embracing the head of the bolt, an arm extending outwardly from said plate and hood and having an apertured horizontally disposed end forming a bearing surface, a pintle secured in said aperture, the length of the slot in the plate being such that the wall member is retained in position on the wall with the axis of the bolt passing through the center of relative movement 70 of the wall member which movement is imparted to said pintle by the door, whereby relative movement of said wall member is prevented.

Signed at Danville, State of Illinois, this 75
16th day of October, A. D. 1917.

DONALD E. WILLARD.
